US00D804309S

(12) **United States Design Patent** (10) **Patent No.:** **US D804,309 S**
Hines (45) **Date of Patent:** **** Dec. 5, 2017**

(54) **METAL BOTTLE**

(71) Applicant: **Ball Corporation**, Broomfield, CO (US)

(72) Inventor: **Linda A. Hines**, Westminster, CO (US)

(73) Assignee: **Ball Corporation**, Broomfield, CO (US)

(**) Term: **15 Years**

(21) Appl. No.: **29/554,999**

(22) Filed: **Feb. 17, 2016**

(51) **LOC (10) Cl.** **09-01**

(52) **U.S. Cl.**

USPC **D9/500; D9/549**

(57) **CLAIM**

The ornamental design for a metal bottle, as shown and described.

DESCRIPTION

FIG. 1 is a front perspective view of a metal bottle; FIG. 2 is a front elevation view thereof; FIG. 3 is a top plan view thereof; FIG. 4 is a bottom plan view thereof; FIG. 5 is a front perspective view of a metal bottle according to an alternative embodiment; FIG. 6 is a front elevation view of the embodiment of FIG. 9; FIG. 7 is a top plan view of the embodiment of FIG. 9; and, FIG. 8 is a bottom plan view of the embodiment of FIG. 9. The broken lines illustrate portions of a metal bottle that form no part of the claimed design.

1 Claim, 4 Drawing Sheets
